SORTING DEVICE

Thomas M. Johnson, Sharen Center, Ohio

Application February 16, 1940, Serial No. 319,266

8 Claims. (Cl. 211—10)

This invention relates to article sorting devices and in particular relates to devices for sorting mail.

A general object of the invention is to provide simple, inexpensive, and effective apparatus for sorting articles, such as mail, in a predetermined arrangement of groups or classes, from which device the sorted articles may be rapidly removed in orderly bundles without disturbing the arrangement of the articles.

Another object of the invention is to provide a device of the character described having spaced elements defining series of pigeonholes for different groups or classes of articles, the spaces between the elements being variable as a group or class of articles placed therein grows in volume.

A further object of the invention is to provide a device for sorting letter mail, or the like, from which device the sorted mail may be quickly scooped up in the hands of the operator in a bundle, without disturbing the sorted arrangement thereof.

Another object of the invention is to provide a device, as described in the last paragraph, in which a support has spaced partitions with indicia thereon for identifying the groups of mail placed between the partitions, said partitions being readily removable and replaceable, as desired.

These and other objects of the invention will be manifest from the following brief description and the accompanying drawings.

Of the accompanying drawings:

Figure 1 is a front elevation of a mail-sorting cabinet or desk embodying the invention.

Figure 2 is a front elevation, on a larger scale, of a portion of the cabinet shown in Figure 1, illustrating the use of the invention for sorting large pieces of mail, such as newspapers.

Figure 3 is a cross-section taken on line 3—3 of Figure 2.

Figure 4 is an enlarged detail view, partly broken away, of one of the letter-sorting racks shown in Figure 1.

Figure 4^a is a cross-section taken on line 4^a—4^a of Figure 4.

Figure 5 is a side elevation as viewed from the right of Figure 4.

Figure 6 is an enlarged cross-section, taken on line 6—6 of Figure 4, but showing the rack emptied of letters.

Figure 7 is a front view, similar to Figure 2, illustrating a modified form of the invention.

Figure 8 is an enlarged cross-section taken on line 8—8 of Figure 7.

Figure 9 is an enlarged fragmentary cross-section taken on line 9—9 of Figure 8.

Referring to Figures 1 to 6 of the drawings, the numeral 10 designates a cabinet or desk, of the type used in post offices for sorting mail, having uprights 11, 11 supporting shelves 12, 12. Letter-sorting racks, indicated generally at 13, 13 are arranged to be either supported across the front of the cabinet or folded out of the way at one end, as will be subsequently described.

The racks 13 are particularly adaptable for sorting letter mail. The shelving within the cabinet proper is subdivided into classified pigeonholes for sorting larger pieces of mail, such as newspapers, although it is understood that the pigeonholes may be used for either newspapers or letters, or both at the same time.

Referring particularly to Figures 2 and 3, pivoted at 14, 14 on the underside of each shelf 12 may be a member 15 arranged to swing from and toward the shelf forwardly of the pivot. Secured to member 15 is a series of upwardly extending partitions 16, 16 in spaced relation to each other, apertures 17 being provided in the shelves for receiving the same. Preferably the partitions 16 are arcuate in shape, the same extending rearwardly concentrically about said pivot. The partitions being so shaped will provide substantially the same support for articles placed between them as would quadrant shaped partitions, for instance, but because of the relative shortness of apertures 17 the tendency of pieces of mail to slip through the apertures, or to become wedged in the apertures against the partitions, will be obviated.

Releasable locking means is provided normally to retain the member 15 in raised position. This may comprise a hook 18 pivoted on the shelf 12 for releasably engaging a pin 19 on pivoted member 15. Other releasable means may be used. The arrangement is such that upon releasing hook 18 the member 15 will drop by gravity, thereby withdrawing the partitions 16 through the openings 17 in the shelf to leave the top surface of the shelf clear and unobstructed.

When the member 15 is inaccessible for raising and lowering it, as described above, as is the case with the members pivoted on the bottom shelves of cabinet 10, the releasable means for retaining member 15 in raised position may comprise a flexible element 20 which extends through an opening 12^a in the cabinet, an eyelet 20^a on the end of element 20 being engageable over a

hook 21 on one of the uprights 11. Releasing the flexible element 20 from hook 21 allows member 15 to drop by gravity, as illustrated in chain-dotted and full lines in Figure 3, the eyelet 26^a engaging the sides of the opening to limit the downward movement of the member and provide means for raising the same when required.

Secured on the front edges of shelves 12 may be metal strips 24 having inwardly turned marginal flanges. Cards 25 having identifying indicia thereon, such as the names and addresses of persons along a mail route, may be removably and replaceably inserted under the flanged portions of the strips 24. The cards are arranged so that the indicia thereon will properly identify the pigeonholes in the cabinet according to predetermined order.

The operation of the apparatus for sorting relatively large pieces of mail, such as newspapers or the like, as indicated at N in Figures 2 and 3, is as follows:

After the articles are arranged in the proper pigeonholes according to their destination along the mailman's route, the operator releases the releasable hook 18, or flexible element 20, as the case may be. This allows the member 15 to swing downward on its pivot 14, by gravity, withdrawing partitions 16 through apertures 17. While the members 15 are so dropping the operator may have his hands ready above the shelf to press all the articles N together into a bundle as the ends of the partitions pass beneath the upper surface of the shelf, as shown in chain-dotted lines in the lower shelf in Figure 2. After this operation is performed in one shelf section of the cabinet, member 15 is retained in lowered position to permit similarly lowering the member 15 above it to form another bundle of sorted articles in the shelf above.

Referring now to Figures 1, 4, 5 and 6, a plurality of the letter-sorting racks 13 may be hinged together in sections at 26, 26 substantially as shown. One end section may be pivoted at 27, 27 to the upright 11 at one end of the cabinet, and the opposite end section releasably secured at 28, 28 to upright 11 at the other end of the cabinet. The construction is such that the racks may be arranged across the front of the cabinet, as shown in Figure 1, for sorting letter mail in the racks, or the sections may be folded upon themselves at one end of the cabinet when not in use, as shown in chain-dotted lines in Figure 1.

Each letter-sorting rack 13 may comprise a panel 30 having a longitudinally extending cavity or groove 31 in a relatively narrow raised portion 30^a on the front face thereof, this cavity having a relatively thin strip 32 of flexible sheet metal or like material secured over it. Strip 32 is provided with a series of longitudinally spaced transverse slits 32^a, 32^a communicating with groove 31, these slits being adapted to receive tongue portions 33 of a series of partitions 34. Partitions 34 may be of thin flexible material, such as metal, cardboard, or the like, shaped substantially as shown and with shoulder portions 34^a for engaging the face of the strip 32 when the partitions are inserted in slits 32^a. As the strip 32 and partitions 34 preferably are made of relatively thin material, the partitions are adapted to lie relatively flat upon each other against the panel 30. The tongues 33 are of such length that they resiliently engage between the slits 32^a and the bottom of groove 31 on an angle, so as normally to retain the partitions in substantially flat relation against the panel. Thus,

the series of partitions will be in stepped relation on panel 30, with a substantial exposed portion 34^b at the outer edge of successive partitions. Suitable indicia may be provided on these exposed portions 34^b, in accordance with the arrangement of an established mail route. With the above described construction the partitions 34 may be easily and quickly removed or replaced, and the spacing between the partitions is readily adjustable.

In the operation of the letter-sorting apparatus the operator places the letters under the proper partitions 34, in the manner shown in Figures 4 and 5, until all letters have been sorted into the various racks. He then engages his fingers under the lowermost letters in a rack 30, on each side of raised portion 30^a, and scoops or lifts the letters out of the rack in a bundle, which may be accomplished without disturbing the sorted arrangement of the letters.

Figures 7 to 9 show a modification of the structure shown in Figures 2 and 3, the essential difference residing in the provision of laterally shiftable partitions 16^a, which may be self-adjusting, these partitions being carried by a member 15^a which is shiftable from and toward the shelf 12^b. To this end, member 15^a may comprise a pair of arms 15^b, extending forwardly from pivots at 14^a in uprights 11^a at opposite ends of a shelf section, and a longitudinally extending rod 15^c fixed at each end to the forward ends of the arms. A series of spaced partitions 16^a, similar in shape to partitions 16 in Figure 3, may be slidably mounted on rod 15^c, a key or spline 15^d, extending the length of the rod, cooperating with keyways in the partitions to prevent relative rotation of the partitions on the rod. Springs 15^e, 15^f extending between adjacent partitions, and between the end partitions and the arms 15^b, yieldingly and self-adjustingly hold the partitions in substantially uniformly spaced relation. The partitions 16^a curve upwardly and rearwardly through a slot 17^a in shelf 12^b when member 15^a is held in raised position, as by means of yielding detents 11^b, 11^b in uprights 11^a, yieldingly engaging the under edges of the arms 15^b. When it is required to lower the partitions it is only necessary initially to force member 15^a downwardly past the yielding detents 11^b, and then let the member drop by gravity.

Each partition 16^a may have a forward extension 16^b to which is secured a metal strip 16^c having inturned marginal portions adapted to receive thereunder a card 16^d upon which is indicia to identify the class or group of mail, or the like, which should occupy an adjacent pigeon-hole. This arrangement is such that the indicia will always be in front of the right pigeon-hole regardless of any variation in size or location of the pigeonhole during a mail-sorting process.

In the use of this construction for sorting large pieces of mail, such as newspapers or the like, the pieces of mail are sorted into the pigeonholes between the partitions 16^a, then after the articles are sorted member 15^a is urged downwardly past detents 11^b, to permit the sorted articles to be removed in an orderly bundle, as described in connection with Figures 2 and 3. If the mail going into one pigeonhole requires greater space than adjacent pigeonholes, the partitions will automatically adjust themselves laterally against the action of the springs 15^e, as best shown in Figure 7.

Thus has been provided simple and effective

apparatus for facilitating the expeditious handling of mail or the like.

Modifications of the invention may be resorted to without departing from the spirit thereof or the scope of the appended claims.

What is claimed is:

1. A sorting device of the character described comprising a support, an apertured shelf mounted on said support, a member mounted to be shiftable from and toward the underside of said shelf, spaced elements on said shiftable member, each element projecting upwardly through an aperture in the shelf to subdivide the space above the shelf into a series of pigeonholes when the member is in raised position, and releasable means for retaining said member in said raised position, said means being releasable to permit said member to shift downwardly and thereby withdraw said elements from the space above the top surface of the shelf.

2. A sorting device of the character described comprising a support, an apertured shelf mounted on said support, a member arranged to swing about a pivot from and toward the underside of said shelf, spaced partitions on said pivoted member, said partitions projecting upwardly through said apertures to subdivide the space above said shelf into a series of pigeonholes, and releasable means for retaining said member in raised position, said means being releasable at will to permit said member to swing downwardly and thereby withdraw said partitions from above the top surface of the shelf.

3. A sorting device of the character described comprising a support, an apertured shelf mounted on said support, a member shiftable from and toward the underside of said shelf, spaced elements on said shiftable member, said elements being shiftable relatively of each other on said shiftable member to vary the normal spaced relation of the elements, each element projecting upwardly through an aperture in the shelf to subdivide the space above the shelf into a series of pigeonholes when the member is in raised position, and releasable means for retaining said member in said raised position, said means being releasable to shift said member downwardly and thereby withdraw said elements from the space above the top surface of the shelf.

4. An article sorting device of the character described comprising a support, a shelf mounted on said support, a member shiftable from and toward the underside of said shelf, spaced elements on said shiftable member, said elements being shiftable relatively of each other on said shiftable member to vary the normal spaced relation of the elements, yieldable means for maintaining said shiftable elements in normally spaced relation, said elements projecting upwardly to subdivide the space above the shelf into a series of pigeonholes when the member is in raised position, whereby through said yieldable means the widths of said pigeonholes will be yieldingly self-adjusting to accommodate articles of varying bulk therein, and releasable means for retaining said member in said raised position, said means being releasable to permit said member to shift downwardly and thereby withdraw said elements from above the top surface of the shelf.

5. A sorting device of the character described

comprising a support, a shelf mounted on said support, a member shiftably mounted in association with said shelf, said member having spaced elements thereon shiftable relatively to each other to vary the normal spaced relation of the elements, and yieldable means for maintaining said shiftable elements in normal spaced relation, said elements subdividing the space above the shelf into a series of pigeonholes, said member being shiftable to withdraw said elements from the space above the shelf.

6. A sorting device of the character described comprising a support, a shelf mounted on said support, a member arranged to swing about a pivot from and toward the underside of said shelf, spaced arcuate elements on said pivoted member, the curvature of the elements being concentric with said pivot, said shelf having apertures for receiving said elements as they are swung about said pivot, said elements projecting upwardly through said apertures to subdivide the space above said shelf into a series of pigeonholes, and releasable means for retaining said member in raised position, said means being releasable at will to permit said member to swing downwardly and thereby withdraw said elements from above the top surface of the shelf.

7. A sorting device of the character described comprising a support, a shelf mounted on said support, a member arranged to swing about a pivot from and toward the underside of said shelf, spaced arcuate elements on said pivoted member, the curvature of the elements being concentric with said pivot, said shelf having a longitudinally extending slot for receiving said elements as they are swung about said pivot, said elements projecting upwardly through said slot to subdivide the space above said shelf into a series of pigeonholes, said arcuate elements being shiftable relatively of each other on said member along said slot to vary the normal spaced relation of the elements to each other, and releasable means for retaining said member in raised position, said means being releasable at will to permit said member to swing downwardly and thereby withdraw said elements from above the top surface of the shelf.

8. A sorting device of the character described comprising a support, a shelf mounted on said support, a member arranged to swing about a pivot from and toward the underside of said shelf, spaced arcuate elements on said pivoted member, the curvature of the elements being concentric with said pivot, said shelf having a longitudinally extending slot for receiving said elements as they are swung about said pivot, said elements projecting upwardly through said slot to subdivide the space above said shelf into a series of pigeonholes, said arcuate elements being shiftable relatively of each other on said member along said slot to vary the normal spaced relation of the element, yieldable means for maintaining said shiftable elements in normally spaced relation, and releasable means for retaining said member in raised position, said means being releasable at will to permit said member to swing downwardly and thereby withdraw said elements from above the top surface of the shelf.

THOMAS M. JOHNSON.
